UNITED STATES PATENT OFFICE.

FREDERICK A. LOVEJOY, OF BOSTON, MASSACHUSETTS.

COMBINED SEWER-PIPE AND MANHOLE.

No. 799,479.

Specification of Letters Patent.

Patented Sept. 12, 1905.

Application filed March 15, 1905. Serial No. 250,315.

To all whom it may concern:

Be it known that I, FREDERICK A. LOVEJOY, a citizen of the United States, residing at Boston, in the county of Suffolk and State of Massachusetts, have invented a new and useful Improvement in a Combined Sewer-Pipe and Manhole, of which the following, taken in connection with the accompanying drawings, is a specification.

10 My invention relates to the combination of sewer-pipes and manholes; and it consists in the peculiar construction and arrangement of the sewer-pipes and their connections in conjunction with manholes, the object being to facilitate and improve the construction of this 15 class of work. This object I attain by means shown in the accompanying drawings, in which—

Figure 1 is a horizontal section of the masonry of a manhole, taken on line C D of Fig. 2, also showing the connected sewer-pipes. Fig. 2 is a vertical section of the same parts, taken on line A B of Fig. 1. Fig. 3 is a plan view of a sewer-pipe having an opening 25 adapted to receive my closure device. Fig. 4 is a cross-section of the sewer-pipe, taken on line E F of Fig. 8; Fig. 5, a detail; Fig. 6, a plan of the cover of the sewer-pipe; Fig. 7, a cross-section of the sewer-pipe, taken on 30 line I J of Fig. 3; Fig. 8, a longitudinal vertical section taken on line K L of Fig. 3. Fig. 9 is a cross vertical section of the pipe, showing the cover and one of the cam-bars that are used for fastening the cover securely 35 to the pipe.

In the drawings, Figs. 1 and 2, a horizontal and vertical system of a sewer-manhole is shown. The construction of this manhole need not be particularly described, as it is not 40 essentially different from the ordinary manhole. The novelty consists in its combination with the sewer-pipes P and m. The pipe P is formed by a sinkage made in the base of the manhole, as shown in Figs. 1 and 2.

45 The pipe m is made of metal of any desired shape and size and is built into the masonry of the manhole. The pipe m has an opening on its upper side, as shown in Figs. 3 and 8. The said opening has located at points on its

edge ears t t. Each of the ears t t has holes r, 50 as shown in Fig. 8. These holes r are made to receive the cam-bolts n x. The opening in the pipe is closed by a cover o, Figs. 4, 6, 8, and 9. This cover has handles u u at its ends and is locked in position by means of cam-bolts x n. These bolts x n are shown in Figs. 5 and 9 and are bent, as shown in Fig. 9, so that when the handle part n is turned down the bend will press with a cam-like action on the cover o and hold it firmly in place. If a 60 very tight joint is required between the cover o and the edge v of the opening in the sewer-pipe m, a gasket W may be used.

In practical operation the manhole-masonry, 65 as shown in Figs. 1 and 2, serves as a firm and reliable support for the sewer-pipes and admits of placing one pipe nearly or quite over the other—that is, the two pipes could be laid in a single trench and the one manhole 70 serve for both pipes. This feature is of especial value in rock-excavation and decreases the cost of excavation in all trenchwork.

The pipe m, as shown, is located above the pipe P, and its flat closed top forms a convenient shelf for the temporary placing of 75 tools, &c.

I claim—

1. The combination of a masonry-built manhole having a sewer-sinkage in the base, and a sewer pipe or pipes passing through said 80 manhole and built into its masonry; substantially as and for the purpose set forth.

2. The combination of a masonry-built manhole having a sewer-sinkage in the base; a sewer-pipe passing through said manhole and 85 built into its masonry, and having a closure device consisting of a cover and cam-bolts and means for operating said bolts; substantially as and for the purpose set forth.

In testimony whereof I have signed my name 90 to this specification, in the presence of two subscribing witnesses, on this 8th day of March, A. D. 1905.

FREDERICK A. LOVEJOY.

Witnesses:

FRANK G. PARKER,
WILLIAM EDSON.
